WILLIAM M. GOODWIN, OF CENTRAL SQUARE, NEW YORK

POPPET-VALVE ACTION FOR INTERNAL-COMBUSTION ENGINES

Application filed November 28, 1927. Serial No. 236,195.

This invention relates to a poppet valve action for internal combustion engines of the multiple cylinder four-cycle type in which the valves are self-closing by means of suitable springs, but are adapted to be opened at regular intervals against the action of said springs by rotary cams acting upon the ends of the valve stems through the medium of what is commonly known as tappets and adjustable connections between the valve stems and tappets for varying the length of the valve stem to conform to the distance between the low points of the cam and valve seats and thereby to assure the proper closing of the valves when the low points of the cams are presented to their respective tappets.

These adjustable connections between the tappet and valve stem are also made to compensate for expansion and contraction of the valve stem under varying temperatures, and in order to maintain proper action of the valve under all temperature conditions it is customary to adjust the connections between the stems and tappets so as to allow a slight play or lost motion under relatively low temperatures sufficient to compensate for the expansion of the valve stem under higher temperatures without opening the valves when the low points of the cams are registered with their respective tappets.

One of the objects of the present invention is to maintain a more uniform temperature of the valve mechanism than has heretofore been practised and thereby to reduce the variations in the effective lengths of the valves by expansion and contraction under varying temperatures of the engine.

Another object is to inclose the cam shaft in a separate oil-containing housing so that the bearings for the cam shaft and connections between the valves and valve stems may be automatically lubricated and the noise of operation of the valves reduced to a minimum.

Another object is to introduce and maintain the oil in the housing under sufficient pressure to hold the tappet connections with the valve stem in contact or against lost motion incidental to the differential lengths of the valve stem under varying temperatures or

rather to take up the lost motion of said connections when the valve stem is contracted to its maximum degree under relatively low temperatures.

A further object is to provide the tappet with a relief passage communicating with the oil chamber in the housing to prevent undue opening of the valves by excess oil pressure in said housing. 55

Another object is to provide one of the cam shaft journals with peripheral oil pockets adapted to successively register with the oil inlet port of the housing for causing intermittent feed of the oil from the housing to the tappet connections with the valve stem and oil circulating ducts in said stem at regular intervals in the operation of the valves. 60

Other objects and uses relating to specific parts of the valve action will be brought out in the following description. 70

In the drawings:—

Figure 1 is a transverse vertical sectional view of a portion of an internal combustion engine and one of the valve actions. 75

Figure 2 is a longitudinal sectional view of an end portion of the cam shaft housing and cam shaft therein together with the adjacent portions of the valve stems and tappets and oil inlet for supplying oil to the interior of the housing. 80

Figure 3 is a detail transverse sectional view of the valve stem. 85

Figure 4 is a transverse sectional view of the cam shaft housing showing a slightly modified form of tappet connection with the valve stem. 85

The oil-containing housing for the cam shaft is similar in some respects to that shown in my pending applications Serial No. 160,406, filed January 11, 1927, and Serial No. 188,471, filed May 3, 1927, in that it consists of a closed tubular unit containing a quantity of oil and the cam shaft end adapted to be inserted into and removed from the frame of the engine when the tappets and their connections with the valve stem are removed therefrom. 95

As illustrated, this device comprises a tubular housing —1— of cast metal or other suit- 100

able material having circular end heads —2— adapted to be supported in corresponding circular openings —3— of the engine frame as —4— and held in operative position by set screws —5— engaging in threaded apertures in the walls of the openings —3— and also engaged in registering sockets in the peripheries of the heads —2— as shown by dotted lines in Figure 1.

10 The tubular housing —1— is provided with an oil chamber —1'— extending therethrough from end to end and having its axis eccentric to and preferably below the axis of the circular heads —2—, the ends of the chamber being closed by removable cap plates —6— held in place by bolts —7—.

15 The chambered portion of the housing —1— is provided with internal annular coaxial bearings —8— in axially spaced relation for receiving and supporting a rotary cam shaft —9— having axially spaced journals —10— and —11— engaging the bearings —8—, said shaft being also provided with axially spaced cams —12— between the journals —10— and —11—.

20 The upper side of the housing —1— is provided with guide openings —13— radial to the axis of the cam shaft —9— and in radial alignment with the cams —12— for receiving cup-shaped piston tappets —14— which are reciprocally movable in their respective guide openings —13— by their corresponding cams —12— and valve-operating springs —15—.

25 The guide openings —13— and piston tappets —14— are preferably cylindrical to permit relative rotation of the piston tappets for changing their lines of contact with the corresponding cams —12—.

30 The lower ends of the piston tappets —14— are substantially flat and tangential to the circular portions of the cams —12— and are provided with relief passages —16— of relatively small area connecting the oil chambers —5— to the interiors thereof for the double purpose of lubricating the tappet connections and also for relieving the piston tappets from excessive pressure of the oil within the chamber —5— to reduce the liability of holding 35 the valves open by such pressure on the underside of the piston tappets.

35 The tappet member —14— is provided with a bearing member —17— loosely resting upon the bottom thereof and provided with a concave upper face —18— engaged by a correspondingly convexed lower end of a valve tappet —19— which is screwed upon the lower threaded end of the valve stem —20— of the poppet valve —21— to form a continuation thereof and permit the valve stem to be lengthened and shortened by relative adjustment of the tappet —19— upon the stem as may be required to enable the valve to close upon its seat as —21'—.

40 The tappet —19— is preferably hollow and

threaded internally for receiving the lower end of the stem —20— and is provided with an oil passage —22— registering with the passage —16— to enable the lubricating oil to pass from the chamber —5— into the interior of the tappet —19— and thence through relieve excess oil pressure upon the lower end of the tappet which might otherwise tend to hold the valve open.

45 A lock nut —23— is also engaged with a threaded lower end of a valve stem —20— and upper end face of the yoke —19— to hold said valve stem and yoke in their relatively adjusted positions.

50 A washer —24— is loosely mounted upon the valve stem —20— and normally rests against the upper end of the lock nut —23— to form a seat for the lower end of the spring —15—, having its upper end abutting against the underside of a lateral projection —25— of the frame —4—.

55 The valve stem —20— extends through a tubular guide sleeve —26— in the bracket —25—, said sleeve serving to guide the valve and stem in its vertical movement.

60 The valve stem —20— is provided with a lengthwise opening extended from its lower end the entire length thereof and into the valve —21— proper a relatively short distance from the upper face thereof so that the upper end of the opening will be closed by the upper portion of the valve.

65 The portion of the opening within the stem —20— between the spring seat —24— and valve head —21— is divided by a lengthwise partition —27— into opposite compartments —28— and —29— having its lower end provided with a lateral offset portion —30— closing the lower end of the compartments —29—, the upper end of said partition being provided with a transverse opening —31— connecting the corresponding ends of the compartments —28— and —29—.

70 The lower end of the compartment —28— communicates with the interior of the stem —20— below the offset portion —30— to allow oil which may pass through the passages —16— and —22— to flow upwardly into the compartment —28— and thence through the passage —31— and downwardly into the compartment —29— which is provided near its lower end with an outlet passage —32— just above the offset —30— and washer —24—, said washer being provided with an additional outlet —35— communicating with the outlet —32— to allow the oil which may escape through the outlet —32— to flow outwardly beyond the periphery of the valve tappet —19— and thence into the crank case of the engine.

Oil shield on valve stem

75 A frusto-conical sheet metal shield —36— is seated at its lower end on the upper face of the washer —24— at the outside of the out-

let openings —35— and in spaced relation to the tube —20— and has its upper end secured to the periphery of said tube above the outlet opening —32— to prevent the oil from passing upwardly along the outside of the valve stem or rather to direct the outlet of the fluid from the passage —32— through the passage —35— where it is free to escape by gravity into the crank case around the outside of the housing —1—.

Oil under abnormal pressure may be supplied to the interior of the housing —1— from any available source of oil supply, as for example from the crank case of the engine, through a supply pipe —37— and passage —38— registering therewith, said supply pipe being engaged in a threaded socket in the outer end of the passage —38— and in the adjacent portion of the frame —4—.

The oil supply passage —38— is preferably formed in the top wall of the housing —1— in radial alinement with the journal —11— on the cam shaft —9—.

This journal —11— is cylindrical and provided with peripheral oil pockets —39— and —39'— arranged in circumferentially spaced relation and each having one end open and its other end closed.

That is, the pocket —39— is open at the end facing the cams —12— at the left hand end of the journal —11— while the open ends of the pockets —39'— face in the opposite direction or in the direction of the remaining two cams, not shown but at the opposite end of the journal —11—, the arrangement corresponding in this instance to a four cylinder engine, but it is evident that if six cylinders are used the journal bearings —11— will be interposed between each pair of cams.

Each journal —11— is provided with a number of pockets corresponding to the number of valves of the engine, one pocket for each valve and they are spaced circumferentially in such relation to each other and to their respective cams —12— that the pocket corresponding to any one of the valves and its operating cam will register with the oil inlet passage —38— at about the time the valve is closing upon its seat or when the lower side of the cam is just beginning to register with the underside of the corresponding tappet —14— and thereby to facilitate the entrance of a fresh charge of the oil through the passages —16— and —22— and thence upwardly through the passage —28— and return through the passages —31— and —29— through the outlets —32— and —35— for cooling the valve and its stem and thereby maintaining a more uniform temperature of the valve and stem to prevent excessive expansion and contraction thereof.

The passage —22— in the lower end of the yoke —19— is controlled by a check valve —40— which is spring-pressed to its seat in the upper end of said passage by a light coiled

spring —41—, Figure 1, to prevent back-flow of the oil from the interior of the valve stem in case the oil pressure in the housing —1— should be excessively lowered or by suction produced by the upward movement of the valve stem and tappet. In the modification shown in Figure 4 the lower end of the valve tappet as —19— bears directly upon the bottom of the cup-shaped piston-tappet —14'— which is provided with a relief passage —16'— for the same purpose as the passage —16— in the piston-tappet —14—.

Otherwise the construction is quite similar to that previously described.

Operation

The liquid oil may be fed through the pipe —37— into the interior of the housing —1— by pump pressure if desired to substantially fill the housing and thereby to supply the necessary lubricant for the bearings of the cam shaft and also the bearings between the cams and tappets, which lubricant is also supplied under the same pressure to the interior of the upflow and return passages of the valve stem through the passages —16— and —22— to return to the crank case from the down-flow passage —29— through the outlet passages —32— and —35—, it being understood that the oil pressure from the source of supply through the passage —38— to the interior of the housing —1— is cut off by the journal —11— except when the pockets —39— and —39'— for their particular valves are registered with said passage —38—.

In other words, the flow of the oil through the upflow and return passages in the valve stem is intermittent and coincident with the registration of the corresponding pocket in the journal —11— with the inlet passage —38—.

This oil pressure in the housing —1— acts upon the lower ends of the piston-tappets —14— to hold the latter in contact with the lower ends of the tappets —19— and serves to take up any lost motion between the tappets and thereby to reduce to a minimum the noise incidental to the operation of the valves by their respective cams aided by the presence of oil at the contact points between the cams and tappets 14 and also between the tappets.

It is to be understood, however, that the oil pressure acting upon the lower ends of the tappets —14— is never sufficient to open the valves against the action of their closing springs —15—.

What I claim is:

1. In an internal combustion engine, a poppet valve having a tubular stem closed at its head and its opposite end opened, a partition extending diametrically across the interior of the tubular stem from side to side thereof for dividing the interior of the stem into opposite cooling channels having a connecting passage adjacent the closed end of the stem, one of

said channels having its inner end closed and provided with an outlet near its closed end, the other channel being in open communication with the open end of the stem, and means for circulating a cooling liquid through said channels from the open end of the stem to said outlet.

2. In an internal combustion engine, a cam shaft housing having a cylindrical chamber containing oil under pressure and provided with a radial guide-opening leading from said chamber to the exterior of the housing, a cam shaft journaled in said chamber, a cam-actuated tappet slidably fitted in said guide-opening and provided with a substantially flat inner end face adapted to be engaged by a cam on the shaft, a poppet-valve having a tubular stem in radial alinement with the guide-opening in the housing and having its inner end open and its outer end closed, a tappet-member adjustably secured to the open end of the valve stem and cooperating with the first-named tappet for transmitting motion therefrom to the valve, said tappets being provided with relatively small relief-passages communicating with the oil-chamber of the housing and with the open end of the valve-stem to permit the passage of oil from said chamber to the interior of the valve stem for cooling purposes, said valve stem having an outlet passage leading from the interior to the exterior thereof to permit the escape of oil therefrom, the cross sectional area of the relief passages being considerably less than the area of the inner end of the first-named tappet to cause the oil pressure within said chamber acting upon the inner end of the piston to hold the first-named tappet in contact with the second-named tappet independently of the cam.

3. In an internal combustion engine, a rotary cam, a housing for the cam having a guide-opening in one side, a tappet slidable in said guide-opening and actuated by said cam, a valve having a tappet bearing against the first-named tappet to transmit motion therefrom to the valve, a spring for closing the valve and urging it and its tappet toward the cam, and means for introducing liquid under pressure into said housing, said liquid-pressure in the housing acting upon the first-named tappet to hold the same in contact with the second-named tappet independently of the cam.

4. In an internal combustion engine, a rotary cam, a housing for the cam having a guide opening in one side, a tappet slidable in said guide opening and actuated by said cam, a valve having a tappet bearing against the first-named tappet to transmit motion therefrom to the valve, a spring for closing the valve and urging it and its tappet toward the cam, and means for introducing liquid under pressure into said housing, said liquid-pressure in the housing acting upon the first-

named tappet to hold the same in contact with the second-named tappet independently of the cam, said tappet and valves having relatively small relief passage communicating with the interior of the housing to relieve the first-named tappet from excess pressure of the liquid in the housing. 70

In witness whereof I have hereunto set my hand this 19th day of November, 1927.

WILLIAM M. GOODWIN. 75
